POWER DRIVEN TOOL

THERON L. HEDGPETH, OAK PARK, ILL., ASSIGNOR TO
DURO METAL PRODUCTS COMPANY, CHICAGO, ILL., A
CORPORATION OF ILLINOIS

APPLICATION JULY 19, 1937, SERIAL NO. 154,342

4 CLAIMS. (CL. 74-217)

The invention relates to power driven tools, and more particularly to power drives therefor.

Although belt drives, slack take-ups therefor, and the use of a single power unit to drive a plurality of power tools are comparatively old, the conventional practice regarding them has been related to large shops and mills wherein power had to be available individually and simultaneously for all of the machines set up on a particular floor, and the necessary millwrighting, shafting, torque speed converters, gears, power transmitters, lag pulleys, slack adjusters and loose connections needed to provide an adequate distribution of power could be isolated and supported overhead where sufficient head space was always available for that purpose.

With the advent of individualized power tools for home workshops, etc., expensive millwrighting and auxiliary power transmitters were out of the question. Power tools had to be provided which could be operated without benefit of conventional millwrighting and also from a single power unit because supplying individual power units with each tool entailed extra cost and great sales resistance. In addition to this, power tool constructions and their operation had to be simplified and rendered readily understandable so that they could be used by those who had little, if any, technical experience, and as a corollary to this proposition, the single power unit supplied had to be thoroughly effective without tinkering and quickly available for all the tools driven thereby.

Consequently, one of the objects of the present invention is to provide improved power tool equipment for home workshops or the like.

Another object of the invention is to provide an improved drive for power tools.

Another object of the invention is to provide an improved belt take-up for power drives.

Another object of the invention is to provide a motor mounting affording an improved belt take-up for power drives.

Another object of the invention is to provide a combined motor mounting and belt take-up affording effective torque drives in a plurality of angularly disposed torque planes.

Another object of the invention is to provide a motor mounting affording automatic drive take-ups in a plurality of angularly disposed directions.

Another object of the invention is to provide a combined motor mounting and belt take-up capable of driving a plurality of variously posi-

tioned tools without auxiliary transmission devices.

Another object of the invention is to provide an improved motor mounting permitting rapid change of speed ratios in multi-speed drives.

Another object of the invention is to provide an improved motor mounting and drive which is simple in construction and operation, effective in use, and inexpensive to manufacture and maintain.

These being among the objects of the invention, other and further objects will become apparent from the drawings herein, the description relating thereto, and the appended claims, these and other objects being contemplated.

Referring now to the drawings generally:

Fig. 1 is a side elevation of a drill press illustrating an embodiment of the invention;

Fig. 2 is an enlarged side elevation of the head portion of the drill press shown in Fig. 1;

Fig. 3 is a top plan view of the head portion shown in Fig. 2;

Fig. 4 is an enlarged section taken on the line 4-4 of Fig. 2;

Fig. 5 is an enlarged section taken on the line 5-5 of Fig. 4;

Fig. 6 is an enlarged section taken on the line 6-6 of Fig. 2;

Fig. 7 is a side elevation similar to Fig. 2 showing the operation of the motor mounting of the invention;

Fig. 8 is a side elevation similar to Fig. 2 showing use of the motor mounting in another relation;

Figs. 9 and 10 are reduced views similar to Fig. 2 illustrating other driving relationships of the motor and a driven member;

Fig. 11 is an enlarged view illustrating another application of the motor mounting; and

Fig. 12 is an enlarged section taken on the line 12-12 of Fig. 11.

Referring now to the drawings in further detail, the preferred embodiment of the invention illustrated will be better comprehended when it is understood, generally, that the motor 10 is pivotally mounted on an adjustable support 12 by a pivot pin 14 for movement about an axis parallel to the torque planes of the drive pulleys 16 and 18 secured on the shaft 30 of the motor 10, and on the driven pulleys 20 and 22 (see Fig. 8) located on the driven shafts 24 and 26 respectively. The location of the pivot pin 14 and the axis of rotation determined thereby is preferably at a point spaced from, not only the torque planes mentioned, but also a plane perpendicular to the

shaft 30 at the center of gravity of the motor 10. The pivot pin 14 in turn may be mounted for bodily movement in three directions, all parallel to one or more of the torque planes mentioned, one direction being curvilinear about the cylindrical standard 32, a second, to and from the standard, and a third, in either direction axially of the standard 32.

The particular structural embodiment employed and illustrated for accomplishing the above set forth objects and results includes a base 34, vertically supporting the cylindrical standard 32. The base 34 is suitably flanged and apertured to receive bolts 36 for securing it relative to a floor or table 37 in a manner preventing a toppling of the standard 32 under the weight of the motor 14, drill head 28, the tiltable work table 38, and the work loads carried thereby.

The drill head 28 rotatably supports the driven pulley 20 by means of a sleeve 40 journalled in the head 28 as at 42 which slidably receives in driving relationship the shaft 24 therethrough for turning the drill chuck 44 at the lower end of the shaft 24 which in turn is fed relative to the work table by means of a quill 46 reciprocated by the manual feed handle 48 in a conventional manner.

Primary adjustment of the drill head 28 relative to the work table 38 is accomplished by means of a bore 50 in the drill head 28 which telescopes over the cylindrical standard 32. The drill head 28 is provided with a slot 52 intersecting the bore 50 so that a winged bolt and nut assembly 54 can be used to contract the sides of the slot in a way establishing a clamping relation at the bore 50 for fixing the drill head 28 on the standard 32 after it has been moved to a desired position both rotatably and longitudinally. The work table 38 is positioned and held in place by like expedient, and this adjustability has a further application, as hereinafter described.

Movable with the drill head 28 and supported by the same clamping means is the motor 10 which is secured to the drill head 28 for movement relative thereto in two directions, one in a direction parallel to the shaft 32 and the other in a direction towards and away from the shaft 32. The parallel movement permits the four step pulleys 16 and 20 to be shifted axially relative to each other (see Figs. 9 and 10), whereby ten different speed ratios between the pulleys are available. The other direction of movement permits tension adjustments for the belt 56 at the different pulley speeds and also for a purpose to be hereinafter further described.

The mounting of the motor 10 for the above movements is accomplished by means of an intermediate member 60 having a guide and groove relation with the head 28 for parallel movements, and a bore and shaft relation with the motor for spacing movements.

The guide is shown at 62 integral with the head 28, extending parallel with the standard 32, and having a wide bottomed slot 64 throughout its length for the reception of the head 66 of a clamp bolt and nut assembly 68 (see Fig. 6). The groove 70, mating with the guide 62, is a part of the intermediate member 60 and is best shown in Fig. 4, wherein shoulder portions 72 thereof straddle the guide 62 to maintain the predetermined alignment of the parts. A bore 74 is provided to receive the shaft of the clamp bolt 68 therethrough to establish the clamping relation desired.

The bore and shaft construction mentioned above comprises two parallel bores 76 extending

through the intermediate member 60 in a direction perpendicular to the groove 70. Telescoping in the bores 76 are two correspondingly parallel rods 78 carried by the support 12, already described, which are locked in the bore against axial displacement in any given position by the winged lock bolt 80.

In this way, it will be observed that the drill head 28 and motor 10 are not only adjustable for movement around and along the standard 32 by means of the bore 50 in the drill head 28, but also are adjustable relative to each other in two directions, spacedly and axially.

Referring now to the particular way in which the motor 10 is mounted for pivotal movement to serve in various capacities to be described, it will be observed that the motor 10 is directly mounted on a base plate 82 by means of nut and bolt assemblies 86 extending through a plurality of slots 84 in the plate 82 and through suitable openings in the base 88 of the motor 10 which coincide with the slots 84. The base plate 82 and the support 12 are hingedly mounted relative to each other by means of the pin 14 traversing intermeshed, coaxially-bored portions 90 carried by the base plate 82 and the support 12. The support 12 is disposed preferably in a vertical plane. The base plate 82 and motor 10, carried on the outside thereof, move arcuately away from the support 12 and upwardly. Downward movement and the weight of the base plate 82 and motor 10 is limited and supported by a set screw and lock nut assembly or stop 92 carried by the support 12.

In this connection, it has already been pointed out that the location of the pivotal axis of the pin 14 is on a line parallel to and spaced from the torque plane of the pulleys 16 and 20, and the plane perpendicular to the shaft 30, which intersects the center of gravity of the motor 10. In this way, upward movement of the motor 10 about the pivot pin 14 shortens the distance between the pulleys 16 and 20 (see Fig. 7) in a way releasing the belt 56 so that it may be transferred to other steps of the pulleys 16 and 20 to establish a different speed ratio therebetween. When the speed ratio has been changed, the motor may be lowered again, and due to the tangential character of the shaft 30 to the arc followed by the motor 10, the increase of distances between the shafts 30 and 24 will lessen with any given equal arcs of travel of the motor 10 as it approaches its resting position against the set screw 92.

Consequently, an improved speed changer and belt take-up is provided wherein a moving of the motor upwardly past the pivot pin 14 creates a release relation whereby the speed ratio change may be accomplished with greater rapidity, and when the motor is moved downwardly, the weight thereof fulcruming about the pin 14 creates a powerful, positive slack take-up for the belt 56 is a way whereby the weight effectiveness of the motor is magnified to a desirable and a practically unyielding degree.

In event the four direct speed ratios, provided by the pulleys 16 and 20, are not enough, it has been pointed out that other speed ratios may be attained by loosening the bolt 68 and moving the auxiliary element 60 up or down sufficient widths of the several steps of the pulleys until the desired speed ratio of the ten available is attained. Thereupon, major variations in the belt 56 tension can be taken up by the rods 78 in the bores 76 through loosening and tightening the winged lock bolt 80, and a closer adjustment

made by adjusting the set screw 92. This makes it possible to have readily at hand a great many more speed ratios in a very simple way, whereby a greater flexibility or adaptability for power drives is provided than would otherwise be possible.

So far, the description of the drawings has been related to the improved mounting and its relation to a drill press. In addition to this, the motor 10, through this improved mounting, is made available for use in many other ways for driving other machinery. For instance, refer to Fig. 8, where the standard 32 is shown set within an offset of a work bench 94 which has other power tools thereon (not shown but represented by pulley 22). The clamp bolt 54 is loosened, the motor 10 and head 28 are lowered to a point below the bench 94 and rotated, if necessary, around the standard 32 to a point where the torque plane of the pulley 22 coincides with the torque plane of one of the steps in pulley 18 when the motor is raised to its horizontal position as shown. The driving relation with the drill pulley 20 automatically becomes inoperative when the motor 10 is raised, and when the motor support is adjusted vertically, either by bolt 54 or by bolt 68, to include the length of the belt 56, then the belt supports the weight of the motor 10 and the weight of the motor 10 serves to maintain automatically the necessary drive tension on the belt 56.

Although one particular application of the motor mounting in its horizontal position is shown, it will be appreciated that the motor mounting can be rotated around the standard 32 to take care of the other driven shafts and pulleys which may be placed where they will overhang other edges of the table adjacent the standard 32. Hereby, the motor can be used as a source of power for many other power tools, and the belt tension maintained automatically for all of them with a very simple adjustment.

Referring now to Figs. 11 and 12, another application of the invention is shown wherein the vertical positions of the drill head 28 and the work table 38 are reversed and the drill head 28 inverted with the quill 48 thereof locked in such a position that the chuck 44 supports and drives a shaper tool 98 above the face of the work table 38. In this event, the motor base plate 82 is held against the stop or lock screw by an L-shaped bolt 100 engaging a positioning offset 102 in the plate 82. The bolt 100 extends through a hole 104 on the support 12 where it is tensionally engaged terminally by a winged nut and washer assembly 106 creating a securement for the plate 102 sufficient to support the motor 10 rigidly against gravity and the tension and drive effect of the belt 56.

Consequently, in addition to the advantages outlined for a faster speed ratio change and the leverage effect on the belt, the present motor mounting makes it possible to utilize the motor for driving pulleys having a variety of angularly disposed torque planes in a manner thoroughly expedient and effective without auxiliary shafting, belt take-ups, or the like, and all necessary belt take-ups are automatic for all the driving relationships available with the mounting and all adjustments are so constructed and arranged that operators without technical experience can operate the tools quite expeditiously.

Although a preferred embodiment of the invention and several applications thereof have been shown and described herein, it will be ap-

parent to those skilled in the art that various modifications, changes, and further applications may be made without departing from the spirit and substance of the invention, the scope of which is commensurate with the appended claims. 5

What I claim as new and desire to secure by Letters Patent of the United States is:

1. In a motor driven tool, the combination of a tool support comprising a column of substantially uniform cross section, with a tool body comprising a member having a split collar embracing said column, threaded means for drawing said collar into clamping engagement with said column, bearing means carried by said member, a tool shaft rotatably mounted in said bearing means and having a plurality of pulleys of different diameters, said collar having a T slot in one side thereof, a mounting plate having a central aperture, a bolt in said aperture, and having its head in said T slot, guides carried by said collar and plate for sliding movement of said plate parallel to said slot, said plate having a pair of transverse guide bores, a pair of guide shafts in said bores, threaded means for clamping one guide shaft in fixed position, a crosshead carried by said guide shafts, said crosshead having a hinge lug, a motor supporting plate having a hinge lug and fixedly secured to a motor, a pintle pivotally connecting said hinge lugs, said motor having a drive shaft with a plurality of pulleys of different diameters, and a belt from a motor shaft pulley to a tool shaft pulley, whereby the weight of the motor may tighten the belt and any pulley on the motor shaft may be used with any pulley on the tool shaft, with the tool shaft and motor shaft parallel to each other and in any of a multiplicity of angular positions.

2. In a motor driven tool, the combination of a tool support comprising a column of substantially uniform cross section, with a tool body comprising a member having a split collar embracing said column, threaded means for drawing said collar into clamping engagement with said column, bearing means carried by said member, a tool shaft rotatably mounted in said bearing means and having a plurality of pulleys of different diameters, said collar having a T slot in one side thereof, a mounting plate having a central aperture, a bolt in said slot, guides carried by said collar and plate for sliding movement of said plate parallel to said slot, said plate having a pair of transverse guide bores, a pair of guide shafts in said bores, threaded means for clamping one of said guide shafts in fixed position, a cross-head carried by said guide shafts, said crosshead having a hinge lug, a motor supporting plate having a hinge lug and fixedly secured to a motor, a pintle pivotally connecting said hinge lugs, said motor having a drive shaft with a plurality of pulleys of different diameters, and a belt from a motor shaft pulley to a tool shaft pulley, whereby the weight of the motor may tighten the belt and any pulley on the motor shaft may be used with any pulley on the tool shaft, with the tool shaft and motor shaft parallel to each other and in any of a multiplicity of angular positions, and means for limiting the pivotal movement of the motor supporting plate with respect to the crosshead.

3. In a motor driven tool, the combination of a tool support comprising a column of substantially uniform cross section, with a tool body comprising a member having a split collar embracing said column, threaded means for drawing said collar into clamping engagement with said col-

umn, bearing means carried by said member, a tool shaft rotatably mounted in said bearing means and having a plurality of pulleys of different diameters, said collar having a T slot in one side thereof, a mounting plate having a central aperture, a bolt in said aperture, and having its head in said T slot, guides carried by said collar and plate for sliding movement of said plate parallel to said slot, said plate having a pair of transverse guide bores, a pair of guide shafts in said bores, threaded means for clamping one of said guide shafts in fixed position, a crosshead carried by said guide shafts, said crosshead having a hinge lug, a motor supporting plate having 15 a hinge lug and fixedly secured to a motor, a pintle pivotally connecting said hinge lugs, said motor having a drive shaft with a plurality of pulleys of different diameters, and a belt from a motor shaft pulley to a tool shaft pulley, whereby the weight of the motor may tighten the belt and any pulley on the motor shaft may be used with any pulley on the tool shaft, with the tool shaft and motor shaft parallel to each other and in any of a multiplicity of angular positions, and means for limiting the pivotal movement of the motor-supporting plate with respect to the crosshead, said means comprising a threaded member carried by one of said plates, and having engagement with the other of said plates.

4. In a motor driven tool, the combination of a tool support comprising a column of substantially uniform cross section, with a tool body comprising a member having a split collar embracing

said column, threaded means for drawing said collar into clamping engagement with said column, bearing means carried by said member, a tool shaft rotatably mounted in said bearing means and having a plurality of pulleys of different diameters, said collar having a T slot in one side thereof, a mounting plate having a central aperture, a bolt in said aperture, and having its head in said T slot, guides carried by said collar and plate for sliding movement of said plate parallel to said slot, said plate having a pair of transverse guide bores, a pair of guide shafts in said bores, threaded means for clamping one of said guide shafts in fixed position, a crosshead carried by said guide shafts, said crosshead having a hinge lug, a motor supporting plate having a hinge lug and fixedly secured to a motor, a pintle pivotally connecting said hinge lugs, said motor having a drive shaft with a plurality of pulleys of different diameters, and a belt from a motor shaft pulley to a tool shaft pulley, whereby the weight of the motor may tighten the belt and any pulley on the motor shaft may be used with any pulley on the tool shaft, with the tool shaft and motor shaft parallel to each other and in any of a multiplicity of angular positions, and means for limiting the pivotal movement of the motor-supporting plate with respect to the crosshead, said means comprising a threaded member having a laterally bent end engaging one of said plates, and having a nut engaging the other of said plates.

HERON L. HEDGPETH.
